UNITED STATES PATENT OFFICE.

JOHN R. MARDICK, OF NEW YORK, N. Y., ASSIGNOR TO ELECTRO METALLURGICAL COMPANY, OF NIAGARA FALLS, NEW YORK, A CORPORATION OF WEST VIRGINIA.

EXPLOSIVE AND METHOD OF PREPARING THE SAME.

1,335,790.

Specification of Letters Patent.

Patented Apr. 6, 1920.

No Drawing.

Application filed August 22, 1918. Serial No. 251,024.

To all whom it may concern:

Be it known that I, JOHN R. MARDICK, a citizen of the United States, residing at New York, in the county of New York and State of New York, have invented certain new and useful Improvements in Explosives and Methods of Preparing the Same, of which the following is a specification.

This invention relates to explosives of the type comprising an oxidizing agent, usually a nitrate, perchlorate or the like; a metallic reducing agent, which preferably contains silicon or an alloy thereof although any of the metallic reducing agents commonly used in this art may be employed; and a plasticizing ingredient, which may be a liquid or easily liquefiable nitro body, usually a dinitro body of the aromatic series. Such explosives may be adapted by appropriate modification of the proportions of the ingredients for either commercial (blasting) or for military purposes.

According to the present invention explosives of this general type are prepared in a cohesive or plastic state which permits them to be readily tamped into conformity with the bore or container. In addition to the components mentioned above, the explosive contains also a normally solid nitro-aromatic body having at least three nitro groups.

One typical explosive in accordance with this invention may comprise:

An oxidizing agent 70-80 parts.
A metallic reducing agent 10-15 parts.
A gelatinized plasticizing ingredient 7-8 parts.

The oxidizing agent may comprise any of the highly oxidizing salts commonly used for this purpose, such for example as ammonium nitrate or perchlorate, the nitrates, chlorates or the like of the alkali metals, barium or lead, or mixtures of such salts.

The metallic reducing agent preferably employed is an alloy of silicon with iron or magnesium. I have used with success ferrosilicon containing 80% or upward of silicon, and also so-called silicids of magnesium containing upward of 50% of magnesium.

The plasticizing ingredient preferably comprises a commercial dinitro body such for example as dinitro toluol, o-dinitro benzol, the liquid nitro xylenes, or equiva-

lent liquid or readily liquefiable nitro-aromatic substances or mixtures thereof, to which has been added a relatively small proportion of a suitable soluble organic body capable of thickening or gelatinizing the dinitro body. The preferred gelatinizers are nitro-cellulose, rosin and nitro-starch. Such gelatinized additions when used in sufficiently small proportions greatly improve the working quality of the explosive, as well as its permanence under atmospheric and other influences, particularly when the oxidizer consists of or contains ammonium nitrate or other hygroscopic salt or compound.

I introduce into the composition a suitable nitro-aromatic substance having at least three nitro groups, such for example as trinitro toluol, picric acid, tri- or tetra-nitro naphthalene, trinitro cresols, or the like. Such bodies are preferably used in excess by weight of the ferrosilicon or other silicon-containing reducing agent, in which case the general formula of the explosive may be essentially as disclosed in the several specific examples given in my copending application Serial Number 207,389, filed December 15, 1917, except that the dinitro toluol of the said formulæ is replaced by a gelatinized plasticizing ingredient. When such tri- or tetra-nitro-aromatic bodies are incorporated in the mixture in the proportions above, the proportion of gelatinized dinitro body therein may usually be diminished to 3-5% by weight of the composition. Since the dinitro bodies act as deadening agents it is preferred in all cases to restrict the proportion used to about the practicable minimum, while securing the necessary cohesiveness or plasticity of the composition as a whole.

A preferred gelatinized plasticizing agent may be prepared by dissolving about 4 parts by weight of nitro-cellulose, rosin or nitro-starch in about 96 parts of commercial dinitro toluol. From 3 to 8 parts of the resulting mixture are then incorporated with the remaining ingredients of the explosive.

Following is a preferred method of compounding an explosive in accordance with this invention, this manipulative method being applicable whatever the precise composition of the explosive mixture:

40 parts of ammonium nitrate in pulverized form are thoroughly dried at a tem-

perature below the melting point of the salt, and mixed with 3 parts of dinitro toluol which has been gelatinized as described above with nitro-cellulose, nitro-starch or 5 rosin. The mixture is thoroughly worked in a kneading machine, preferably at about 80-100° C., until the surfaces of the nitrate are thoroughly coated. The heat is then cut off and there are introduced gradually 10 into the kneading machine and in the order named, 15 parts of trinitro toluol; 32 parts of lead nitrate; and 10 parts of ferrosilicon. Kneading is continued until the mixture is entirely homogeneous, whereupon it is 15 charged into cartridges by tamping, in the manner commonly practised with dynamite.

Small proportions of wood flour or other combustible, say about 3-5%, and about 1/4 or less of calcium carbonate or other anti- 20 acid body, may be incorporated with the other components of the mixture.

I claim:—

1. An explosive composition containing an oxidizing salt, a metallic reducing agent, 25 a normally solid nitro-aromatic body having at least three nitro groups, said nitro-aromatic body being present in quantity not less than that of the metallic reducing agent, and a gelatinized plasticizing ingredient, 30 the latter in about the minimum proportion required to render the composition cohesive or plastic.
2. An explosive composition containing an oxidizing salt, a reducing agent containing metallic silicon, a normally solid nitro-aromatic body having at least three nitro groups, said nitro-aromatic body being 35

present in quantity not less than that of the reducing agent, and a gelatinized plasticizing ingredient, the latter in about the 40 minimum proportion required to render the composition cohesive or plastic.

3. An explosive composition containing an oxidizing salt, a reducing agent comprising magnesium and silicon, a nitro-aromatic 45 body having at least three nitro groups, and a gelatinized plasticizing ingredient, the latter in about the minimum proportion required to render the composition cohesive or plastic.

4. An explosive composition containing an oxidizing salt, a reducing agent comprising magnesium and silicon, a normally 50 solid nitro-aromatic body having at least three nitro groups, said nitro-aromatic body 55 being present in quantity not less than that of the reducing agent, and a gelatinized plasticizing ingredient, the latter in about the minimum proportion required to render the composition cohesive or plastic.

5. An explosive composition containing an oxidizing salt, a reducing agent containing metallic silicon, a normally solid nitro-aromatic body having at least three nitro groups, said nitro-aromatic body being 65 present in quantity not less than that of the reducing agent, and a gelatinized dinitro body, the latter in about the minimum proportion required to render the composition cohesive or plastic.

In testimony whereof, I affix my signature.

JOHN R. MARDICK.
